(57) **CLAIM**

The ornamental design for a set of reflective elements for a tire, as shown and described.

DESCRIPTION

FIG. 1 is an isometric view of a reflective tire marking system showing my new design;

FIG. 2 is a right side elevational view of the reflective tire marking system of FIG. 1;

FIG. 3 is a left side elevational view of the reflective tire marking system of FIG. 1;

FIG. 4 is a front plan view of the reflective tire marking system of FIG. 1;

FIG. 5 is a rear plan view of the reflective tire marking system of FIG. 1;

FIG. 6 is a top plan view of the reflective tire marking system of FIG. 1; and,

FIG. 7 is a bottom plan view of the reflective tire marking system of FIG. 1.

The portions of the figures that are presented in broken lines merely illustrate the environment of the design and are not part of the claimed design.
